DESK BLOTTER

William Macowski, Montclair, N.J., assignor to Ketcham
& McDougall, Inc., Roseland, N.J., a corporation of
New Jersey

Filed Nov. 16, 1965, Ser. No. 88,120

Term of patent 14 years

(Cl. D74—1)

FIG. 1

FIG. 2

FIG. 2 is a top plan view thereof;

FIG. 3 is a front elevational view; and

FIG. 4 is a side elevational view thereof on a larger scale.

I claim:

The ornamental design for a desk blotter, as shown.
